EDWARD T. MCKEAN, OF HAMMONTON, NEW JERSEY.

Letters Patent No. 100,173, dated February 22, 1870.

IMPROVED CAR-COUPLING.

The Schedule referred to in these Letters Patent and making part of the same.

To all whom it may concern:

Be it known that I, EDWARD T. MCKEAN, of Hammonton, in the county of Atlantic, and in the State of New Jersey, have invented certain new and useful Improvements in Car-Couplings; and do hereby declare that the following is a full, clear, and exact description thereof, reference being had to the accompanying drawing, in which—

Figure 1 is a bottom plan view of my coupling when attached to a railway-car.

Figure 2 is a vertical cross-section of the car-coupling on the line $z z$ of fig. 1.

Figure 3 is a longitudinal vertical section of the same on the line $y y$ of fig. 1.

Figure 4 is a side view of the draw-bar with a broken vertical section of the jaw, showing its interior with the draw-rod in position.

Figure 5 is the device for disconnecting the draw-rod from the draw-bar.

Like letters of like kind represent like parts in each figure.

The object of this invention is the construction of a car-coupling by which railway-cars will be self-coupling, not only on a straight track, but upon a curve, without any dangerous exposure to the brakeman, and may be instantly uncoupled by a pressure of the foot.

And the nature of the invention consists in a draw-bar made in two parts pivoted together, the front end of which has a jaw for the reception of the draw-rod, while the rear ends are provided with springs which serve to keep the jaw closed; in the peculiar form of the interior of the jaw; in the devices by which the jaw is opened and the draw-rod released; in the novel construction of the bumper and its longitudinal adjustability; in the vertical adjustability of the bumper; and in the general arrangement of its several parts.

In the drawings—

A represents the platform or end of the bottom frame of a railway-car, the under side of which is shown in fig. 1, to which under side the coupling is attached.

B is a bumper-head, of an elliptical form on its front presentation, with its shortest axis in vertical position, and of suitable thickness from front to rear. This bumper-head has in its center an opening, funnel-shaped both in front and in the rear, with the large part outward, but much more flaring in front than in the rear, and projects when in position a suitable distance in front of the end of the frame A.

Guide-rods C, the forward ends of which, provided with screw-threads, pass through the bumper-head, which is provided with corresponding screw-threads, extend back in parallel lines under the platform A. These rods pass through slotted boxes, D, rigidly secured to the under side of the front sill of the frame A, and through the boxes E rigidly secured to the

under side of a cross-sill of said platform A, and terminate in heads outside of said boxes E.

The slotted boxes D have their openings in a vertical direction, allowing a vertical play of the guide-rods within them.

Directly behind the slotted boxes D is a yoke, F, with the arms downward, through each of which the guide-rods C pass, the center of which yoke is provided with a hook, which passes under the center of the elliptic spring G and operates it.

This elliptic spring G extends across the bottom of the frame A, close to its end, and the ends of said spring are secured to the side sills of said frame.

The draw-bar H, having its front end nearly coincident with the front of the frame A, is placed directly between the guide-rods C and equidistant from them, with its center longitudinally in a line with the center longitudinally of said guide-rods. This draw-bar is made of two parts, halved into and crossing each other, arranged vertically one above the other and pivoted together at their intersection, so as to allow of a simultaneous vertical separation or closing of the ends.

The front of this draw-bar forms a jaw, a, which is provided in its central front end with a mouth, b, flaring outwardly, which mouth connects with a throat, c; also in the longitudinal center of said jaw, which throat is of the shape of the frustum of a cone longitudinally, with the larger end forward and the smaller end to the rear. The diameter of this throat being larger than the opening from the mouth into the throat, a shoulder, d, is left in the throat all around said opening.

Upon the upper and lower sides of the draw-bar are elliptic springs, e, rigidly secured at one end to the draw-bar near its front end, and pressing upon the rear ends of said draw-bar, so as to keep the jaw a closed.

The rear ends b' of the draw-bar are somewhat separated, and the extremity of each is pivoted to a link, J, which is in turn pivoted upon the connecting-bar g of the rear cross-head K, on either side of a hook, h, to which in turn is attached one end of a chain, k, which passes along by the side of the draw-bar forward, and is attached at its other end to a lever, L.

This lever rises vertically from a roller, M, which is suitably pivoted in boxes rigidly secured to the under side of the platform A.

At right angles with said lever L, a lever, N, is secured to said roller, and, passing toward the rear, is pivoted to another lever, O, which passes up through the platform, and is there provided with a head, P.

The cross-head K, before mentioned, consists of two sleeves, m, which play freely upon the guide-rods C, and are joined together by the connecting-bar g. A similar cross-head, K', plays freely upon the guide-rods C nearer their front, and its connecting-bar g' passes

through the draw-bar H at its point of intersection of parts, and forms the pivot upon which the jaw *a* operates.

Spiral springs Q embrace the guide-rod C, between the cross-heads K and the slotted boxes D, protected at each end by suitable washers.

Like springs, R, embrace said guide-rods between said slotted boxes D and the bumper-head B, also protected at the rear end by suitable washers.

A draw-rod, S, of suitable length, provided at each end with a head, *n*, of the form of the frustum of a cone, with the smaller part of said head outward, and so much larger than the body of the rod that a shoulder, *o*, is left behind each head. This head and shoulder will be of such shape and size as to be readily inserted and held in the throat *c* of the draw-bar H.

The method of operating my device is as follows:

The coupling being attached to two cars, in one of them the draw-rod will be in position, one end of it being held in the jaw of one of the draw-bars, and the whole rod pointing forward and a little downward. As the other car approaches almost to the point of contact, the free end of the draw-rod will enter through the bumper-head of the other car and into the jaw behind the bumper-head, open said jaw by its peculiar shaped head, and be immediately secured therein by the action of the springs upon the rear end of the draw-bar. The brakeman, by pressure upon the lever-head P within convenient reach of his foot, releases the end of the draw-rod attached to the draw-bar of his car.

Among the advantages of this device are the following, viz:

Security of life and limb to the brakeman, who need not get between the cars for any purpose connected with this device. Self-adjustability, which will take place even on a curve, if the cars are brought sufficiently near, by reason of the flaring mouths of the bumper-head and of the draw-bars. Comfort to passengers and avoidance of shocks by the use of springs, and the support of the draw-bars upon cross-head moving in guide-rods. Great convenience and speed in uncoupling. Security of draught while the cars are in motion, the jaw holding the head of the draw-rod tightly, and yet admitting, by its flexibility of position, considerable play vertically, and a little laterally.

In addition, it is believed that this coupling gives security to the lives of passengers, by reason of the inclination of the draw-rod to disengage itself upon

any violent and large lateral motion, as of a car quitting the track.

Having thus fully described my device and set forth its merits,

What I claim as my invention, and desire to secure by Letters Patent, is—

In railway-car couplings, attaching the bumper-head to parallel guide-rods which extend longitudinally under the car bottom and play in boxes at either end of said guide-rods, the boxes at the front ends of said rods being deeply slotted, so as to allow a vertical movement of the front ends of said rods.

—Also, the combination of the bumper-head B, the guide-rods C playing vertically in the slotted boxes D, and the spring G for regulating the vertical movement of the bumper-head, as set forth.

Also, the combination of the bumper-head B, the guide-rods C playing vertically in the slotted boxes D, the draw-bar H, the connecting-bar *g*', and cross-head K', for the purpose of a vertical, simultaneous, and coincident movement of the said draw-bar and bumper-head, as set forth.

Also, the combination of the draw-bar H, the cross-heads K and K', the connecting-bars *g* and *g*', and the guide-rods C, for the purpose of a horizontal independent movement of said draw-bar, as set forth.

Also, the combination of the bumper-head B, the guide-rods C, the boxes D and E, for the purpose of a horizontal independent movement of said bumper-head, as set forth.

Also, pivoting the draw-bar upon the connecting-bar of a cross-head, substantially as set forth.

Also, the draw-bar H, substantially constructed, arranged, and operating as above set forth.

Also, the devices by which the draw-rod S is released, consisting of the links J, the hook *h*, the chain *k*, the levers L and N, and roller M, when constructed and operating as set forth.

Also, the bumper-head B, provided with the guide-rods C, in combination with the draw-bar H, when constructed, arranged, and operating substantially as set forth.

In testimony that I claim the foregoing, I have hereunto set my hand this 15th day of October, 1869.

EDWD. T. MCKEAN.
